ATTORNEY

UNITED STATES PATENT OFFICE.

WILLIAM HENRY, OF McCARTHY, TERRITORY OF ALASKA.

AUTOMATIC STOP.

Application filed February 27, 1925. Serial No. 12,117.

To all whom it may concern:

Be it known that I, WILLIAM HENRY, a citizen of the United States, residing at McCarthy, in the Territory of Alaska, have 5 invented new and useful Improvements in Automatic Stops, of which the following is a specification.

This invention contemplates the provision of an automatic stop for the turn table of 10 a talking machine or the like, and embodies amongst other features, a resilient element designed to engage the stop lever to normally hold the stop spaced from the table, and adapted to be actuated by the reproducer 15 arm of the machine to effect a release of the lever, as the arm assumes its final position at the completion of the record.

The nature and advantages of the invention will be better understood when the following detailed description is read in connection with the accompanying drawing, the 20 invention residing in the construction, combination and arrangement of parts as claimed.

25 In the drawing forming part of this application, like numerals of reference indicate similar parts in the several views, and wherein:

Figure 1 is a fragmentary plan view of 30 the machine showing how the invention is used.

Figure 2 is a sectional view taken on line 2—2 showing how the resilient element engages the stop lever and the position it occupies when it is moved away from said lever.

Figure 3 is a view partly in section of the stop and lever therefor.

Referring to the drawing in detail, A 40 indicates generally a portion of the talking machine or the like of well known construction and wherein 10 represents the turn table against the periphery of which the stop 11 is adapted to bear in order to check 45 the rotation of said table when desired. This stop 11 is carried at one end of the lever 12 and is pivoted as at 13 and associated with the suitable casing 14 which is secured to the top of the machine by suitable fastening elements 15. This lever is secured to 50 one end of a coiled spring 16, the other end of which is secured to the casing 14 in any suitable manner, the spring being utilized to automatically draw the stop 11 into active

engagement with the periphery of the table 55 10 for the purpose above stated.

In accordance with the present invention, use is made of a resilient element 17 which has one end secured to the top of the machine as at 18, although the element itself is 60 spaced from the machine as clearly shown in Figure 2. This element is preferably shaped in the manner shown in Figure 2, that is it is formed to provide a shoulder 18 which is adapted to be engaged by the lever 65 12 when it is desired to hold the stop 11 spaced from the table 10 as shown by full lines in Figure 1. The other end of this resilient element 17 is formed with an eye 19, and this eye is connected to one end of a 70 cord or other flexible element 20 as shown in Figure 1. The other end of the element 20 is secured to a lug 21 which projects outwardly from a clamp or ring 22 which surrounds the reproducer arm B of the machine 75 and secured thereto for movement therewith. The length of flexible element 20 can be varied as the occasion may require, and while this may be accomplished in any suitable manner I preferably make use of a turn 80 buckle 24 of well known construction.

In practice, after the record has been placed upon the table and the reproducer arm B swung outwardly to its initial position, with respect to the record, the lug 21 85 occupies the position shown by full lines in Figure 1. The lever 12 can then be arranged in contact with the shoulder 18 of the resilient element 17, thus holding the stop 11 spaced from the table 10. During the playing 90 of the record the reproducer arm B moves inwardly toward the center of the record as it is of course understood, and during this movement of the arm, the lug 21 is swung to the dotted line position shown in 95 Figure 1, thus exerting a pull upon the flexible element 20 which in turn flexes the resilient element 17, moving the latter to the position shown by dotted lines in Figure 2. Manifestly, when the element 17 is moved 100 into this position, the shoulder 18 is separated from the lever 12, whereupon the spring 16 functions to automatically draw the stop 11 to its active association with the table 10. The invention in its entirety is very simple 105 in construction, and can be quickly and easily attached to any make of machine of the class in question.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

- 5 1. An automatic stop for the turn table of a talking machine comprising a spring pressed pivoted lever, a stop carried thereby, a resilient element designed to engage said lever and hold the stop spaced from the periphery of the table, and means connecting the element with the reproducer arm of the machine, whereby said element is flexed to release said lever, and said arm assumes its 10 final position at the completion of the record.
- 15 2. An automatic stop for the turn table of a talking machine comprising a pivoted lever, a stop carried thereby, a resilient element having one end secured to the machine, said element being designed to engage said lever and hold the stop spaced from the periphery of the table, a clamp secured to the reproducer arm of the machine for movement therewith and including a lug, and a 20 connection between said lug and the free end of said resilient element whereby the latter

is flexed to release said lever as the arm assumes its final position with relation to the record.

35 3. An automatic stop for the turn table of a talking machine comprising a spring pressed pivoted lever, a stop carried thereby, a resilient element having one end secured to the machine, and the other end free, a shoulder formed on said element and arranged to engage said lever to hold the stop spaced from the periphery of the table, and a connection between the free end of said element and the reproducer arm, whereby 40 said element is flexed to release said lever when the arm reaches the limit of its inward movement.

4. An automatic stop for the turn table of a talking machine comprising a spring 45 pressed pivoted lever, a stop carried thereby, a resilient element having one end secured to the machine, a shoulder formed on said element and arranged to engage said lever to hold the stop spaced from said table, and a 50 flexible element terminally secured to the other end of said resilient element and reproducer arm of the machine, whereby said resilient element is flexed to release the lever when said reproducer arm reaches the limit of its inward movement and means for adjusting the length of said flexible element.

In testimony whereof I affix my signature.

WILLIAM HENRY.
